UNITED STATES PATENT OFFICE.

LEWIS B. DOMAN, OF EAST SYRACUSE, NEW YORK, ASSIGNOR TO THE AMPHION PIANO
PLAYER COMPANY, OF SYRACUSE, NEW YORK, A CORPORATION OF NEW YORK.

TONE-MODULATING APPARATUS FOR SELF-PLAYING MUSICAL INSTRUMENTS.

1,256,988.

Specification of Letters Patent. Patented Feb. 19, 1918.

Application filed February 14, 1916. Serial No. 78,174.

To all whom it may concern:

Be it known that I, LEWIS B. DOMAN, a citizen of the United States of America, and resident of East Syracuse, in the county 5 of Onondaga, in the State of New York, have invented new and useful Improvements in Tone-Modulating Apparatus for Self-Playing Musical Instruments, of which the following, taken in connection with the accompanying drawings, is a full, clear, and 10 exact description.

This invention relates to certain improvements in tone-modulating apparatus for self-playing musical instruments of the class 15 set forth in my pending application, Serial No. 38,181, filed July 6, 1915, involving the use of a web-controlled, pneumatically-operated tone-controlling valve in combination with means for operating said valve at will 20 independently of the web-controlled operating means.

In the application referred to, when the valve is operated through the medium of pneumatics controlled by special apertures 25 and ducts in the note sheet and tracker bar, respectively, the manual or finger lever by which the valve is operated independently of said pneumatics is caused to vibrate in response to the movements of the valve, and 30 with some users this vibration is objectionable.

The main object, therefore, of my present invention is to provide simple means whereby the manual may remain at rest 35 when the tone modulation is produced automatically.

In other words, I have sought to provide convenient means for connecting and breaking the connection between the manual 40 and valve so that the latter may be operated automatically independently of the manual or by the manual independently of the automatic operating means.

Other objects and uses relating to specific 45 parts of the invention will be brought out in the following description.

In the drawings—

Figure 1 is a perspective view, partly 50 broken away and partly in section, of the valve chest and valve-controlling means for

the tone-modulating device, together with portions of the note-sheet and tracker.

Fig. 2 is an enlarged longitudinal sectional view of the clutch and its operating means for making and breaking the connection between the valve-operating lever and valve. 55

Fig. 3 is an enlarged sectional view of the auxiliary valve for controlling the operation of the clutch-operating pneumatic. 60

Fig. 4 is a perspective view of a tone-modifying device to which my invention is applied.

Figs. 5 and 6 are, respectively, a longitudinal vertical sectional view and a transverse vertical sectional view of the valve chest shown in Fig. 1. 65

As illustrated, the controlling means for the tone-modulating apparatus comprises the slide valve —1— and a pair of similar pneumatics —2— for shifting the valve in reverse directions through the medium of pawls —3— which are connected to their respective pneumatics —2— for engaging reversely arranged tooth racks —4— on the valve. 70

The pneumatics —2— are preferably secured to opposite ends of a valve chest —5— which is adapted to be connected by a pipe or conduit —6— to the wind chest of a tone-modifying device —A—, said wind chest being in turn connected by pipe —b— to a wind-inducing device —B—, a portion of which is shown in Fig. 1. 80

The valve —1— serves to connect any one 85 of a series of, in this instance three, conduits —7— with an exhaust conduit —7'—, the latter being connected to the exhaust chamber of the valve chest —5—, Fig. 6 while the conduits —7— are connected to a corresponding number of tone-modulating pneumatics —a— which coöperate with a tension regulating pneumatic —a'— to control the expression. 90

Communication between the valve operating pneumatics —2— and the exhaust chamber as —6'— of the valve chest —5— is controlled by suitable valves —5'— and primary pneumatics —8—, not shown, but located within the wind chest, the primary 100

pneumatics being connected by conduits —8— to special ducts —28— in a tracker bar —29— where they are controlled by corresponding apertures —31— and —31'— 5 in a note sheet, —30—.

The main feature of my invention however resides in the connection between the valve —1— and a suitable operating manual therefor, such for example as a finger lever 10 —9—, which is secured to one end of a rock shaft —10— in combination with means presently described for making and breaking such connection.

This rock shaft is journaled in suitable 15 bearings —11—, preferably on the under side of the instrument frame below the keyboard, and is provided with a suitable clutch section —12— rigid thereon and adapted to coöperate with a co-axial clutch section 20 —13— which is loose on the shaft and normally engaged with the section —12— to turn with the shaft, but is slid able out of engagement therewith against the action of a retracting spring —14— to avoid turning 25 with the shaft when desired, said spring being interposed between the clutch section —13— and a suitable collar —15— on the shaft.

The clutch section —13— is provided 30 with a crank arm —16— which is connected by an extensible link —17— to the valve —1— to enable said valve to be adjusted manually through the medium of the finger lever —9— when the members —12— and 35 —13— are engaged.

Suitable means is provided for disengaging the clutch section —13— from its companion section —12— to allow the shaft —10— and finger lever —9— to remain at 40 rest when the valve —1— is operated by the pneumatics —2—, said means consisting, in this instance, of a relatively small pneumatic —18— suitably mounted upon the supporting frame of the instrument and 45 having its movable side provided with a forked arm —19— engaging in an annular groove in the clutch section —13— so that when the pneumatic —18— is deflated by exhausting the air therefrom, it will shift 50 the clutch section —13— out of engagement with the clutch section —12— against the action of the spring —14— for the purpose described.

The pneumatic —18— is connected by a 55 conduit —20— to a port —21— in a valve board —22—, said valve board being provided with an additional port —23— which is adapted to be connected by a conduit —24— directly or indirectly to the wind- 60 inducing device.

Movable along and upon the valve board —22— is a valve —25— normally covering the exhaust port —23— and adapted to connect and disconnect the port —21— with

and from said port —23—, the valve —25— 65 being operated at will through the medium of an operating rod —26— within easy reaching distance of the operator.

When no provision is made in the note sheet and tracker bar for the operation of 70 the tone-modulating device, such modulation may be effected through the medium of the lever —9—, in which case the valve —25— would simply be shifted to uncover the port —21— to the atmosphere, thereby 75 allowing the spring —14— to engage the clutch sections —12— and —13— for completing the connection between the lever —9— and valve —4—.

It is evident, however, that even though 80 the note sheet and tracker bar may be provided with the necessary apertures and ducts for automatically controlling the operation of the tone-modulating device, it will be possible at all times to introduce other modulations as may be desired by properly manipulating the lever —9—.

On the other hand if the tone-modulating device is controlled automatically through 90 the medium of the specially perforated web and ducts in the tracker bar, the transmission of motion from the valve —1— to the lever —9— may be prevented by simply shifting the valve —25— so as to cover both of the ports —21— and —23—, thereby 95 causing the deflation of the pneumatic —18— to withdraw the clutch section —13— from engagement with the section —12—, in which position it will be held as long as the instrument is being played, thereby allowing the lever —9— and its shaft —10— to remain at rest.

What I claim is:

1. In a tone-modulating device for self-playing musical instruments, the combination with a web-controlled, pneumatically-operated tone-controlling valve, of means operable at will for shifting said valve independently of the web-control and including a clutch. 105

2. In a pneumatic self-playing musical instrument, a tone-modulating device having web-controlling means and hand-controlling means including means for rendering the hand-controlling means inactive 115 while the web-controlling means is active.

3. In a self-playing musical instrument, a tone-modulating device having a tone-controlling valve, web-controlled pneumatics for operating said valve, and manually operated means for operating the valve independently of the pneumatics and including a clutch. 120

4. In a self-playing musical instrument, a tone-modulating device having a tone-controlling valve, web-controlled pneumatics for operating said valve, manually operated means for operating the valve independ- 125

ently of the pneumatics and including a clutch, and separate pneumatic means for releasing the clutch.

5. In a self-playing musical instrument, a tone-modulating device having a tone-controlling valve, web-controlled pneumatics for operating said valve, manually operated means for operating the valve independently of the pneumatics and including a 10 clutch, separate pneumatic means for re-

leasing the clutch, and means operable at will for controlling the operation of the last-named pneumatic means.

In witness whereof I have hereunto set my hand this 11th day of February 1916. 15

LEWIS B. DOMAN.
